UNITED STATES PATENT OFFICE.

WILLIAM M. BROWN, OF GIBSONBURG, OHIO.

HOISTING-MACHINE.

No. 900,979.

Specification of Letters Patent.

Patented Oct. 13, 1908.

Application filed June 6, 1908. Serial No. 437,070.

To all whom it may concern:

Be it known that I, WILLIAM M. BROWN, a citizen of the United States, and a resident of Gibsonburg, in the county of Sandusky and State of Ohio, have invented a certain new and useful Hoisting-Machine; and I do hereby declare the following to be a full, clear and exact description of the invention, such as will enable others skilled in the art to which it appertains to make and use the same, reference being had to the accompanying drawings, and to the figures of reference marked thereon, which form a part of this specification.

15 My invention relates to hoisting machines, and particularly to portable machines of this class for use in raising sucker-rods, tubing or other parts from oil or other classes of wells, or for lowering such parts therein, but it is 20 not restricted to such use.

25 The object of my invention is the provision, in combination with a vehicle or other portable mount, of simple and efficient means for raising the mast from or lowering it to reclining position relative thereto and shifting it to enable it when raised to be positioned at either side of the vehicle as the position of the parts to be operated on relative to the vehicle or mount may require.

30 The operation, construction and arrangement of the parts of the invention are fully described in the following specification, and illustrated in the accompanying drawings, in which,—

35 Figure 1 is a cross-section of the vehicle associated with my invention with the mast set up in operative position at one side thereof, the upper portion of the mast being broken away. Fig. 2 is a side elevation 40 thereof with the mast and operating mechanism shown in dotted lines in reclining position on the vehicle. Fig. 3 is an elevation of the upper portion of the mast and associated parts. Fig. 4 is an elevation of the 45 upper portion of the mast with a portion of the lower section in longitudinal section. Fig. 5 is an enlarged longitudinal section of a portion of the lower mast section and the base portion of the upper mast section, and 50 Fig. 6 is a transverse section on the line $x-x$ in Fig. 5.

55 Referring to the drawings, 1, 1 designate two beams which are supported by the running gear of a suitable vehicle and have their ends rigidly connected by the front and rear cross-pieces 2, 2, which preferably project

above the beams and form pillow-blocks for the purpose hereinabove described.

Connecting the beams 1, 1 intermediate their ends and preferably at or near the center thereof is a platform 4, to the top of which is suitably swiveled a block 5 for horizontal pivotal movement. Hinged to the top of the block 5, as at 6, for oscillation in a vertical plane is a second block 7, from one side of which rigidly project the spaced bars or side frame pieces 8, 8. These bars each hinge at their outer ends, as at 9, to the lower cross-piece or base of a frame 10 to which the lower end of the mast or pole 11 is fixed in a suitable manner, thus enabling the mast to be elevated relative to the frame formed by the block 5, bars 8, 8 and base of the frame 10, as shown in Figs. 1 and 2, or placed in reclining position thereon, as shown by dotted lines 75 in Fig. 1. The mast when in reclining position rests on a pillow-block 12 on the top of the block 7. Each bar 8 is shown as comprising two sections, which are secured together in a manner to permit longitudinal adjustment 80 thereof if desired.

Mounted longitudinally of the block 5 on the side thereof opposed to the bars 8, 8, is a shaft 13, which has its ends adapted to receive a crank and carries two rack-pinions 14 85 one of which is disposed at each side of the mast 11 when in reclining position. A rack-bar 15 co-operates with each pinion, and each is slidingly held in engagement therewith by a guide 16, which is loosely carried by the 90 shaft to enable its bar to have a pivotal as well as a longitudinal movement. Each rack-bar 15 carries the two spaced sheaves 17, 17 at its upper end between which is passed a cable 18, the upper or mast end of 95 which is attached to the mast or pole 11 above the end of the rack-bar when in elevated position, as at 18' in Fig. 3, while the lower end thereof attaches to and is adapted to wind on a windlass 19, carried by the bars 100 8, 8 transversely thereof. The windlass 19 is adapted to be turned by a crank and carries a ratchet-wheel 20 with which a pawl 21 engages to normally prevent an unwinding of the two cables 18 therefrom. Attached 105 to the upper end of each rack-bar 15 is one end of a guy-cable 22, the other end thereof being carried down in advance of the mast-frame 10 and attached to the base thereof, as at 23.

When the mast and its base-frame 10 are in reclining position on the swinging-frame

which carries the base-frame, the base end of the mast is counterbalanced to a considerable extent by the other end thereof so that the outer end of the swinging-frame can be 5 easily raised to horizontal position from the lowered position shown in Figs. 1 and 2 and swung around with its load to enable them to rest on the top of the vehicle longitudinally thereof. When in this position the base- 10 frame 10 rests on the pillow-block 2 of the vehicle while the forward portion of the mast rests on the other pillow-block 2 thereof, as shown by dotted lines in Fig. 2. One pillow-block 2 is preferably hinged, as at 3, to enable 15 it to be swung down when the mast is being swung around and then to be raised beneath the mast to cause the part resting on the other block to be forcefully held to its seat to prevent vertical oscillatory play of the mast 20 when the vehicle is in motion.

The hoisting-cable 24 of the machine passes up over a sheave 25 at the top of the mast and then down and attaches at one end to a drum 25', which is carried by the mast- 25 frame 10 transversely thereof, and has power applied thereto in any suitable manner.

The mast 11 is shown as having an upper section 11', which loosely telescopes within the lower section 11 to permit relative longitudinal adjustment thereof. An adjustment of the sections is effected through the medium of a cable 26, which has one end attached to a windlass 27 carried by the frame 10, thence passes up over a sheave 28 near the upper 35 end of the lower mast section, thence down into said section between it and the upper section and under a sheave 29 carried at the lower end of the upper section, the other end of the cable being then carried up between 40 the two sections and attached to the lower section as at 30.

31 designates a clutch which is carried at the upper end of the lower mast section and coöperates with it and the upper section to 45 maintain them in fixed adjustment as soon as strain is applied to the upper section, thus relieving the adjusting-cable 26 of all working strain on the mast. The clutch may be released by a downward pull on the outer end 50 of the lever 32. In raising the mast to operative position from the horizontal reclining position shown by dotted lines in Fig. 2, the pillow-block 2, which is hinged, is swung down to enable the portion of the mast in engagement with the other pillow block to be 55 tilted free therefrom and the mast to be then swung transversely of the wagon with its base on the desired side thereof and in contact with the ground, as shown by full and dotted 60 lines in Fig. 1. The rack-bars 15 are now elevated and run out by a turning of the shaft 13 in the proper direction until the guy-cables 22 are drawn taut, as shown, and are locked in such position by inserting locking 65 pins 15^a through apertures in the guides 16

and registering apertures 15^b in the rack-bars. The windlass 19 is now turned to shorten the cable 18 to effect a raising of the outer end of the mast, and the rack-bars are further run out as the raising operation may 70 require. As the mast is raised from the position shown in dotted lines in Fig. 1 the cables 18 work over the lower sheaves 17 of the respective rack-bars, and by the time the mast has been elevated to vertical position 75 the upper sections of the cables 18 have swung over into engagement with the upper sheaves 17, thus tending to steady and stop the forward movement of the mast when it has reached a predetermined point past a 80 vertical. It will, of course, be understood that guy-ropes are attached to the upper end of the mast to steady it when past or in vertical position.

It is apparent that I have provided a simple and highly efficient means for raising and lowering the mast and enabling it to be placed in reclining position longitudinally of the vehicle or raised at either side thereof as the position of the article to be operated on 85 relative to the vehicle may require.

I wish it understood that I do not desire to be restricted to the exact details of construction and arrangement of the parts shown and described, as obvious modifications will be 90 apparent to persons skilled in the art.

Having thus described my invention, what I claim as new and desire to secure by Letters Patent, is,—

1. In combination, a portable mount, a 100 frame mounted thereon for both horizontal swivel and vertical oscillatory movements, a mast hinged to said frame, and mechanical means for effecting a raising or lowering of the mast relative to the frame and bracing 105 the mast when raised.

2. In combination, a portable member, a swivel-frame mounted thereon, a mast associated with the frame and adapted to be elevated or lowered to reclining position thereon, a cable attached to the mast, and rack-bar and pinion mechanism coöperating with the cable to effect a raising of the mast from 110 reclining position.

3. In combination, a portable member, a 115 swivel-frame mounted thereon, a mast associated with the frame and adapted to be elevated or placed in reclining position thereon and moved therewith, a windlass carried by the frame, a cable having its opposite ends 120 attached to the windlass and mast, and rack-bar and pinion mechanism coöperating with the cable and windlass to effect a raising of the mast from reclining position.

4. The combination with a portable 125 mount, of a frame mounted thereon for horizontal and vertical swinging movements, a mast hinged at its base to the outer end of said frame, a windlass carried by the frame, rack-pinions carried by said frame, rack-

bars coacting with the pinions, cables attached to the mast and windlass and having their intermediate portions in engagement with the upper ends of the rack-bars whereby a shortening of the cables when the bars are elevated and the mast reclining will effect a raising of the mast.

5. In combination a portable mount, a frame mounted thereon for both horizontal 10 swivel and vertical oscillatory movements, a mast base hinged to the outer end of said frame and adjustable relative to the swivel axis thereof, and a mast fixed to said base.

6. In combination a support, a mast 15 hinged thereto to be placed in elevated or reclining positions, a cable attached to the mast, and rack-bar and pinion mechanism coöperating with the cable to effect a raising or lowering of the mast.

20 7. In combination a portable member, a mast hinged to said member, a windlass carried by said member, cables attached to the mast and windlass, and rack-bar and pinion mechanism coöperating with the cables and 25 windlass to effect a raising of the mast.

8. In combination, a support, a mast hinged thereto to be raised and lowered, a windlass, carried by the support, a cable attached to the mast and windlass, a pinion, 30 carried by the support, means for turning the pinion, and a rack-bar coacting with and adapted to have pivotal and longitudinal

movements relative to the pinion, said rack-bar having a transverse opening at one end through which the cable passes. 35

9. In combination, a support, a mast hinged thereto, a windlass and a pinion carried by the support, means for turning the pinion, a rack-bar coacting with the pinion, a pair of sheaves carried at one end of the 40 rack-bar and spaced longitudinally thereof with their peripheries facing each other, a cable attached to the mast and windlass and passing between said sheaves for the purpose described. 45

10. In combination, a support, a mast hinged thereto, a windlass and a pair of pinions carried by the support, a rack-bar coacting with each pinion and adapted to have longitudinal and pivotal movements relative 50 thereto, a pair of sheaves carried at an end of each rack-bar and spaced longitudinally thereof, a separate elevating cable passed between each pair of sheaves and attached to the mast and windlass, and a guy-cable attached to the sheave end of each rack-bar, substantially as described. 55

In testimony whereof I have hereunto signed my name to this specification in the presence of two subscribing witnesses.
